UNITED STATES PATENT OFFICE.

LOUIS SCHWARTZ, OF NEW YORK, N. Y., ASSIGNOR TO EAGLE CHEMICAL WORKS, OF SECAUCUS, NEW JERSEY, A CORPORATION OF NEW JERSEY.

RECEPTACLE FOR ETHYL CHLORID.

SPECIFICATION forming part of Letters Patent No. 701,274, dated May 27, 1902.

Application filed February 6, 1902. Serial No. 92,771. (No model.)

To all whom it may concern:

Be it known that I, LOUIS SCHWARTZ, a citizen of the United States, and a resident of the city of New York, borough of Manhattan, in the county and State of New York, have invented new and useful Improvements in Receptacles for Ethyl Chlorid, of which the following is a full, clear, and exact description.

My invention relates to improvements in receptacles for ethyl chlorid and other fluids—such, for example, as in devices for use by dentists or surgeons for producing local anesthesia; and one object that I have in view is to provide an improved form of spray-nozzle for a receptacle adapted to contain a highly volatile fluid, such as a fluid of the class described, said spray - nozzle adapted to so tightly close the receptacle as to thoroughly prevent the escape of the fluid.

A further object of the invention is to provide a nozzle with packing means of a character which will not be affected by or deteriorate under the influence of the fluid contained in the receptacle; and a further object is to provide an improved form of nozzle by which streams or jets of the fluid may be projected on converging lines to a certain part in which it is desired to produce local anesthesia—as, for instance, in dental surgery.

With these ends in view the invention consists in the novel construction, arrangement, and combination of parts which will be hereinafter fully described and claimed.

Reference is to be had to the accompanying drawings, forming a part of this specification, in which similar characters of reference indicate corresponding parts in all the figures.

Figure 1 is a side elevation of a receptacle equipped with a spray device as contemplated in one embodiment of my invention. Fig. 2 is another side elevation showing a receptacle equipped with two forms of spray devices also as contemplated by the present invention. Fig. 3 is an enlarged vertical section through one form of the spray device, showing it in the open or active position. Fig. 4 is a rear elevation of the adjustable nozzle. Fig. 5 is an enlarged vertical section through another form of the spray device, illustrating the nozzle constructed with capillary passages arranged to direct the jets on converging lines.

Fig. 6 is a detail plan view of the adjustable nozzle, illustrating the series of converging branch passages arranged to discharge to one of the two converging jet-passages; and Fig. 55 is a detail section of one means for attaching the metallic tube to the neck of the receptacle.

5 designates the receptacle, which is preferably a glass tube, although the form of the receptacle is not material. As shown by Fig. 1, the receptacle is provided with a contracted neck 6 at one end, and this neck is surrounded by a metallic collar 7. A metallic tube 8 is inserted in the neck 6 of the receptacle, and 60 said tube 8 is adapted to be sealed in any approved way within the neck 6. The metallic tube 8 is of a very small diameter as compared with that of the receptacle 5, and said tube is bent at a point outside of the collar 7, so as to 65 form the inclined or angular length 9.

The particular form of the metallic tube 8 and the location of this tube at one end of the receptacle 5 are not material. In Fig. 2 the receptacle is provided at one end with the 75 neck 6 and at its other end with a corresponding neck 6^a, each neck being surrounded by a metallic collar, the collars for the two necks being indicated at 7, 7^a, respectively. In the neck 6 is sealed the angular or bent tube 8 9; 80 but in the neck 6^a is sealed a straight metallic tube 10, the latter being disposed in the plane of the longitudinal axis of the receptacle 5. The metallic tube or tubes are provided with spray - nozzles, the same being 85 shown by Figs. 3 to 6, inclusive. In Figs. 1 and 2 the spray-nozzles on the bent or angular tubes are adapted to assume positions inclined to the axis of the receptacle, thus making it convenient for the dentist or surgeon 90 to hold the receptacle in a certain position when the fluid is to be directed against the part in which it is desired to produce local anesthesia. The relation of the spray device to the receptacle, however, is not material, 95 and this spray device may be attached to the metallic tubes 10 at the left-hand end of Fig. 2, so that it will occupy a coaxial relation to the receptacle.

I will now proceed to describe the improved 100 form of the spray device, reference being had to Figs. 3 to 6, inclusive. The metallic tube,

either 8 or 10, is externally threaded for a portion of its length, as indicated at 11, and the end face of this metallic tube is formed by grinding or finishing the same in any suitable way, so as to constitute a valve-seat. (Shown very clearly by Figs. 3 and 5.)

12 designates the cap, which is provided with a collar 13 at its rear end, and in this collar is formed a female-threaded passage, 10 adapted to have the threaded length 11 of the metallic tube screwed therein. The cap 12 is provided with a chamber 14, the same terminating at one end at the collar 13 and the other end of said chamber opening through the 15 opposite end portion of the cap, said chamber being internally screw-threaded, preferably from end to end thereof. The threaded length 11 of the metallic tube is projected or extended into the inner or rear portion of the 20 chamber 14, and on this projecting end of the tube is screwed a plug 15, the latter having a central threaded perforation by which it may be screwed upon the tube. Between the bottom or inner closed end of the chamber 14 25 and the plug 15 is interposed a metallic washer 16, the latter being of concavo-convex form in cross-section and stamped or struck up from a single piece of elastic sheet metal. The edge portion of this elastic washer 30 bears against the inner closed wall of the chamber in the cap; but the convex central portion of said washer bears against the adjustable disk 15, so as to offer resistance to the movement of said disk 15 in an inner 35 direction. The disk is provided with sockets or openings 17, adapted to receive a suitable implement whereby the disk may be screwed on the metallic tube to compress the washer 16 more or less, said washer being adapted to 40 exert tension on the plug or disk in order to crowd the threads of the latter against the threads on the threaded length 11 on the metallic tube. The washer thus co-operates with the disk or plug in a manner to thoroughly 45 prevent any leakage of the fluid between the tube and the cap 12, which is screwed thereon, and as the disk, the washer, and the tube are made of metal said parts will not deteriorate under the influence or action of the 50 liquid with which the receptacle 5 is filled or charged.

18 designates the metallic nozzle, which consists of a cylindrical body and a tapering nozzle portion, said cylindrical body being 55 externally threaded and adapted to be snugly screwed into the female-threaded chamber 14 of the cap. A cavity or recess 19 is formed centrally in the inner portion of this nozzle, and in said cavity is secured a valve 20. This 60 valve is made of a material which will not be affected by the action of the fluid in the receptacle, and at the same time the said valve is adapted to be forced tightly against the seat which is formed by the end face of the 65 metallic tube. I have found vulcanized fiber to satisfactorily meet the need for a valve

adapted for use under the conditions recited, and I therefore prefer to employ a plug or solid body of vulcanized fiber which is seated in the cavity 19 and exposed through the inner face of the nozzle. 70

The nozzle shown by Figs. 3 and 4 is provided with an axial capillary passage 21 and with a plurality of converging capillary ducts 22, the same having communication at their front ends with the axial passage 21, and the other ends of said ducts opening through the inner face of the nozzle in a way to form a series of equidistant ports, as indicated by Fig. 4. I prefer, however, to employ a nozzle having converging jet-passages 23 24, as indicated by Fig. 5. These converging jet-passages are supplied with the fluid by a plurality of converging ducts 25, and, as shown by Figs. 5 and 6, these ducts 25 are disposed in two groups, one group 25 of said ducts being adapted to supply the fluid to one passage 23 and another group 25 of the ducts being adapted to supply the passage 24. The two groups of ducts open through the inner face of the nozzle, and the liquid is adapted to pass from the chamber 14 into the ducts and thence to the passages 23 24, whereby two jets are projected by the nozzle on converging lines. 95

In operation it is only necessary to partly unscrew the nozzle 18 within the threaded cap 12, thereby withdrawing the valve 20 from engagement with the end face or valve-seat of the metallic tube. The highly-volatile fluid contained in the receptacle escapes readily through the tube 9 and into the chamber 14, from whence it passes into the ducts and through the jet passage or passages of the nozzle. The fluid can escape only through the nozzle, and it cannot by back pressure pass between the metallic tube and the cap, because the tension exerted by the washer on the disk wholly overcomes any leakage through the spray device at this point. To 105 cut off the escape of the fluid, it is only necessary to screw the nozzle into the cap, and the valve 20 is thus adapted to tightly and securely close the sealed metallic tube, thereby preventing any loss of the fluid by leakage or evaporation. It should also be noted that the plug or disk 15 forces the edge portion of the elastic metallic washer against the inner end of the cap, and the washer thus makes a tight joint around the tube adjacent 110 to the place where the tube passes through the cap, thereby preventing the leakage of the fluid from the cap at the rear closed side thereof. 115

Instead of sealing the metallic tube directly 120 into the neck 6 or 6^a of the receptacle I may adopt the construction shown by Fig. 7. A threaded metallic nipple 26 is cemented to the neck of the receptacle, and on this nipple is screwed the collar 7 or 7^a, the latter being internally threaded for the purpose. The metallic tube and the collar are made in a sin- 130

gle piece of metal, and the end 27 of the tube is extended into the cavity of the collar. Around this end 27 of the tube is fitted a cementitious plug 28, which is adapted to bear against the nipple 26 and to make a tight joint between the collar and the nipple, the latter being cemented to the receptacle. The cementitious plug is made, preferably, of gelatin, mucilage, and starch, because I have found that a mixture of these ingredients has the peculiar property of hardening under the action of the fluid with which the receptacle is charged.

Having thus described my invention, I claim as new and desire to secure by Letters Patent—

1. In a device of the class described, the combination with a tube, of a cap attached thereto, means substantially as described for making a tight joint between the tube and the cap, and a nozzle screwed in said cap.

2. In a device of the class described, the combination with a tube, of a non-adjustable cap attached to the tube by a threaded joint, means for locking said cap against rotation and producing a tight joint between the tube and the cap, and a nozzle attached to the cap.

3. In a device of the class described, the combination with a tube, of a non-adjustable cap attached to said tube by a threaded joint, a washer and nut within said cap and locking the same against rotation on the tube and forming a tight joint between said parts, and a nozzle.

4. In a device of the class described, the combination with a tube, of a non-adjustable chambered cap attached to said tube by a threaded joint, an elastic washer within said

chamber of the cap, a nut screwed on the tube and impinging the washer, and a nozzle. 40

5. A device of the class described comprising a tube, a cap thereon, a nozzle screwed into said cap and provided with capillary jet-passages and with two series of capillary ducts, said series of ducts communicating 45 individually with said jet-passages, and said jet-passages being disposed in converging relation and opening at different points through the active end or face of the nozzle, and a valve adapted to close the tube. 50

6. A device of the class described comprising a chambered cap, a nozzle screwed into said cap and provided with converging jet-passages which are supplied by a plurality of branching ducts adapted to communicate 55 with said chamber, said jet-passages opening at different points of the active end or face of the nozzle, and a valve carried by the nozzle within the branching ducts and adapted to close the source of supply to the chamber 60 of said cap.

7. A device of the class described, provided with a threaded tube, a cap screwed to said tube, a disk screwed on the tube, a spring-washer acting against said disk and crowding 65 the threads thereof into engagement with the threads of the tube, and an adjustable nozzle attached to the cap.

In testimony whereof I have signed my name to this specification in the presence of 70 two subscribing witnesses.

LOUIS SCHWARTZ.
